UNITED STATES PATENT OFFICE.

EDWARD R. LINEBAUGH, OF BARBERTON, OHIO, ASSIGNOR TO THE DIAMOND MATCH COMPANY, OF CHICAGO, ILLINOIS, A CORPORATION OF ILLINOIS.

SHEET-REGISTERING DEVICE.

1,399,064.

Specification of Letters Patent.

Patented Dec. 6, 1921.

Application filed February 17, 1921. Serial No. 445,596.

To all whom it may concern:

Be it known that I, EDWARD R. LINEBAUGH, a citizen of the United States, and resident of Barberton, in the county of Summit and State of Ohio, have invented certain new and useful Improvements in Sheet-Registering Devices, of which the following is a specification.

This invention relates to sheet registering mechanisms for Gordon printing presses and the like; and particularly to that type of such mechanisms in which is included a registering arm which is mounted and operated to effect limited endwise and lateral movement of the successive sheets imposed on the platen, and accurately position them against end and side stops on the platen. Heretofore two interchangeable registering devices, adapted respectively for right and for left hand shifting of the sheets, have been provided; either of such devices being employed as occasion required.

The object of my invention is to provide a unitary reversible device, of simple and efficient construction, which can be readily applied to the press in such a manner as to effect the requisite registry movement of the sheet either toward the left or the right hand side of the platen, as desired.

Accordingly my invention comprises various novel features of construction and combinations of parts which will be hereinafter described and claimed.

In the drawings—

Figure 1 is a plan of a platen, and adjuncts, equipped with a reversible sheet registering device embodying my invention, said device being mounted to shift the sheet from right to left of the platen, and the gripper bar being shown in down position.

Fig. 2 is a vertical section on the line 2—2 of Fig. 1.

Fig. 3 is a view similar to Fig. 1, but showing the gripper bar in raised position and the registering device shifted toward the left of the platen.

Fig. 4 is a view similar to Fig. 1, but showing the sheet-registering device in reversed position to shift the sheet from left to right.

Fig. 5 is a detail perspective view of the detachable members of the registering device.

Referring to the drawings, 10 designates the platen of an ordinary Gordon press, and 11 and 12 designate the end and side stops, respectively, for the sheets of paper imposed on the platen.

13 designates the oscillatory gripper bar mounted at one end of the platen, and 14 designates spaced apart gripper fingers carried by said bar and adapted to be swung thereby at intervals upon and from the successive sheets on the platen, as usual.

Fast on the end of the platen, adjacent the gripper bar, is a bracket 15 upon which is adapted to be detachably supported an oscillatory head 16. This head, in its preferred form, comprises a body of suitable shape and size having two pivot holes 17 spaced apart in a line extending intermediate of the ends and transversely of the head, and having a pin 18 and a slotted extension 19 at the respective ends of the head and in a line extending longitudinally of the head and midway between said pivot holes. In the present instance one end of the pin is inserted into a suitably-disposed hole in the head and detachably held in place by means of a screw 18'. The head is adapted to be detachably and pivotally mounted on the bracket by means such as a screw 20 passed through one or the other of the holes 17 and screwed into a tapped hole 27 in the bracket, whereby the extension 19 will project toward the right or the left hand side of the platen as desired. The pin 18 extends loosely through a transverse eye 21 in an arm 22 so as to have a freely movable connection with the latter, which arm is adapted to be detachably secured to the gripper bar by means such as the screw 23 entered in a suitably-disposed screw-hole 24 in the bar. When the parts are thus assembled the pin and eye connection between the arm and the head are so positioned in relation to the axis of oscillation of the gripper bar, that the eye moves in a short arc of a circle, the pin moving freely in the eye as the position of the latter is shifted. Hence, the head, during the forward or active movement of the gripper bar and its fingers toward the platen, is turned in a short arc about the pivot screw 20, and then in the back stroke of said bar the head is returned to its original position.

The gripper bar is provided with at least two screw-holes 24 spaced apart correspondingly with the respective locations of the pin 18 as prescribed by the right or left hand disposition of the head on the bracket 15, and hence the arm 22 can be supported on the bar in engaging relation to said pin according to the position occupied by the head. Provision is thus afforded for the effective

right or left hand operation of the head during the active movement of the gripper bar, as desired. In Figs. 1, 2 and 3 the position of the head for left hand registration is shown, and in Fig. 4 the position of the head for right hand registration is illustrated.

The extension 19 of the head is slotted, as at 25, to receive a registering arm 26 which, being suitably held in the extension, over- 10 hangs the platen in a path between the end stops 11 when the head is mounted on the bracket; said arm thus partaking of the oscillatory motion of the head 16. The arm 26 is detachably and adjustably held in the 15 slotted extension 19 by means, preferably, of a suitably-disposed set-screw 19'. The forward end of the arm 26 is provided with a spring clip 28 which is formed and arranged to grasp and hold the end of a sheet of paper (a) inserted therebetween and supported on the platen, as usual; whereby during the movement of the arm toward the right or the left hand side of the platen, as predetermined by the particular pivotal mounting of 25 the head on the bracket 15, the sheet is bodily shifted in relation to the end and side stops in a manner to effect the requisite endwise and right or left hand registration.

I have shown the bracket 15 as provided 30 with an additional screw hole 27' which is suitably spaced from the hole 27, and the bar 13 as provided with an additional pair of screw holes 24' in proper relation to the hole 27', so that the head and its appurte- 35 nances can be set at another position on the bracket and gripper bar in order to operate upon sheets of a different size, whether the device be positioned for either right or left hand registration. Of course the num- 40 ber and position of the correlated holes in the bracket and bar may be increased to enable the positioning of the device at various adjacent points effective to accommodate sheets of various sizes, as occasion may re- 45 quire.

From the foregoing it will be seen that my invention provides a simple reversible device which can be applied with facility to a press in such a manner as to accomplish 50 either right or left hand registration of the successive sheets imposed on the platen, as desired; the requisite operation of the de- 55 vice being predetermined and effected by properly positioning the head 16 on the bracket 15 so that the extension 19 of the head will extend therefrom toward the right or left hand side of the platen; by applying the registering arm to said extension in such a manner that the clip of the arm will be 60 positioned to receive and grasp the proximate end of the sheet, and by properly positioning the arm 22 on the gripper bar, as previously explained.

Without limiting my invention to the de-

tails of construction disclosed, excepting as 65 expressly defined in the appended claims, what I claim is—

1. In a printing press having a platen and sheet stops thereon and having a vibratory gripper bar coöperating with said platen, a 70 unitary reversible sheet registering device comprising an oscillatory member having spaced-apart portions for interchangeable pivotal mounting adjacent the platen, a sheet receiving and registering arm detachably se- 75 cured to one end of said member, and means providing a freely movable connection for the opposite end of said member and either of two locations on the bar as required by the pivotal mounting of the said member, 80 whereby the said member, arm and connect- 85 ing means can be associated and mounted in operative relation to each other to effect either right or left hand registry movement of the said arm.

2. In a printing press having a platen and sheet stops thereon and having a vibratory gripper bar coöperating with said platen, a reversible sheet registering device comprising an oscillatory head, means for detach- 90 ably and pivotally supporting said head at either of two spaced-apart portions thereof adjacent one end of the platen, a sheet re- 95 ceiving and registering arm detachably se- 100 cured to said head laterally of the pivotal portions of the latter, an element movably connected with the said head beyond the opposite side of said pivotal portions, and means for detachably supporting said ele- 105 ment at either of two spaced-apart locations on the gripper bar.

3. In a printing press having a platen and sheet stops thereon and having a vibratory gripper bar coöperating with said platen, a reversible sheet registering device comprising a pivot supporting element arranged at 105 one end of the platen, an oscillatory head having therein two spaced-apart pivot holes in a line extending intermediate the ends and transversely of the head, and having 110 a projecting member and registering-arm sup- 115 port at the respective ends of the head and in a line extending longitudinally of the head and midway between said pivot holes, a pivot adapted to be passed through either of said holes and engaged with said pivot sup- 120 porting element, a sheet registering arm de- 125 tachably secured to the arm support of the oscillatory head, an arm loosely coupled to said projecting member, and means for de- 130 attachably connecting said arm to the gripper bar at either of two spaced-apart locations on the latter.

Signed at Barberton, in the county of Summit and State of Ohio, this 9 day of February, A. D. 1921.

EDWARD R. LINEBAUGH,
